UNITED STATES PATENT OFFICE.

ALEXANDER BOUCHER, OF DEDHAM, MASSACHUSETTS.

INDEX.

Application filed February 7, 1925. Serial No. 7,620.

My invention relates to an index and particularly to an index in which a turnable structure is equipped with a multiplicity of indexes disposed about the axis of said 5 structure.

The general object of my invention is to provide an index of the indicated type in which the individual indexes are so mounted as to be capable of being slid laterally outward to increase the visibility of the index. 10

More specifically, an object of the invention is to provide a structure of extreme simplicity and the maximum strength and of a character to promote convenience in the 15 assemblage of the parts and in manipulating the index when in use.

Reference is to be had to the accompanying drawings forming a part of this specification, it being understood that the drawings are merely illustrative of one example 20 of the invention.

Figure 1 is a perspective view of an index embodying my invention;

Figure 2 is a view partly in vertical section and partly in elevation, showing one of 25 the indexes and the means for mounting the same.

Fig. 3 is a sectional detail on the lines 3—3 of Fig. 2.

30 In carrying out my invention in practice in accordance with the illustrated example, a base 10 is provided, supporting a reel comprising a lower disk 11, a spindle 12 rising therefrom, and an upper disk 13.

35 Supported on the disks 11, 13 and disposed about the axis of the spindle of the standard 12 is a series of frames 14, each comprising a horizontal top member 15 and a horizontal bottom member 16, said members 40 15, 16 and the vertical member joining the same constituting a frame generally of U-shape. The said frame is engaged with the disks 11, 13 by pivots 17 received in registering holes 111 and 113 in the disks 11 and 45 13.

Extending from the top and bottom frame bars 15, 16 are horizontal arms 18. Said arms 18 are pivoted to terminals 19 on the bars 15, 16, respectively and directed 50 respectively downwardly and upwardly.

The arms 18 serve to support frames 20, each of said frames being supported by a pair of the arms 18 so as to lie in a vertical plane. Each frame 20 receives a panel 21 55 adapted to bear printed or written index

matter. The frames 20 are essentially U-shape consisting of a top and bottom member and an outer vertical member. The inner end of said frame is open for the entrance and removal of a panel 21 which is held between spaced inwardly directed flanges 22 on the frame 20. The frame 20 is formed at the top and bottom with longitudinal slots 23 closed at the inner ends as at 24, the arrangement serving to permit longitudinal sliding movement of the frames 20 with their panels 21 relatively to the arms 18, to dispose a panel and its frame in an outer position for increased visibility as indicated by the dotted lines in Figure 1. 70 Thus, with the described construction, each frame and the arms 18 and index panel 21 may be turned about the members 19 as a center. Also, the arms 15 carrying the arms 18, frame 20 and panel 21 may be swung 75 with the pivots 17, as a center. In addition the panel 21 with its frame 20 may slide longitudinally on the bars 18 and the panel 21 may be removed and replaced when desired. 80

I would state, furthermore, that while the illustrated example constitutes a practical embodiment of my invention, I do not limit myself strictly to the exact details herein illustrated, since, manifestly, the same can be considerably varied without departure from the spirit of the invention as defined in the appended claims. 85

Having thus described my invention, I claim:

1. An index including a structure mounted to turn about a vertical axis, a series of frames mounted on said structure to turn therewith, a series of index panels, and means supporting said index panels and connected with said frame to have sliding movement inward or outward in the general plane of the panel. 95

2. An index including a supporting structure, a series of panels disposed about the axis of said structure, and means supporting said panels from said structure and permitting turning movement of the panels about vertical axes intermediate their ends, and sliding movement of the panels in their own planes toward or from the vertical axis of said structure. 100

3. An index including a vertically disposed structure, frames disposed in vertical planes about said structure, index panels, 110

and frames for said index panels, said last-mentioned frames being rotatably and slidably supported on the first-mentioned frames.

5. An index including a vertically disposed structure, frames disposed in vertical planes about said structure, index panels, and frames for said index panels, said panel frames being mounted in the first frames to

slide in the plane thereof and to turn about their own vertical axes.

5. An index including a structure mounted to revolve about a vertical axis, frames mounted to swing laterally on said structure, arms on said frames at the top and bottom, and frames slidably mounted on said arms and adapted to receive index panels.

ALEXANDER BOUCHER.
